[57] ABSTRACT

A well safety valve closable by a predetermined flow rate including a housing connectible on a locking mandrel, inlet ports in the housing, a valve seat downstream from the ports, a pressure reducing flow bean in the housing downstream from the valve seat, a valve member in the housing upstream of the valve seat and engageable with the valve seat to shut off flow through the valve, an operator piston slidable in the housing and exposed on a first side to well pressure upstream of the valve seat, a piston rod secured from the piston to the valve member, an annular chamber within the housing around the piston rod, a pressure sensing tube on the valve member extending through the flow bean connecting with a passage in the piston rod opening into the annular chamber to apply fluid pressure from downstream of the flow bean to a second side of the piston for operating the piston responsive to a flow rate induced pressure differential, a spring in the annular chamber biasing the piston and rod in a direction to open the valve, a detent assembly between the housing and piston to insure valve closing without throttling, and a self-centering seal assembly around the piston rod within the housing sealing one end of the annular chamber.

WELL SAFETY VALVE

This invention relates to well safety valves and more particularly relates to a well safety valve operative responsive to a predetermined flow rate in a well.

In the operation of petroleum oil and gas wells, a condition may develop which causes abrupt increases in the flow rates as a result of various types of damage which may occur at the wellhead or along the tubing of the well. For example, physical destruction, particularly in offshore wells, may occur due to storms and the like causing the sudden opening of the wellhead resulting in a dangerous loss of fluids to the surrounding sea. While there are several styles or types of flow rate responsive well valves available, they generally require flow rates which are substantial in volume and below which it remains possible for severe damage to occur to a well resulting in leakage which does not cause the required flow rate to be developed to cause closing of the valve. Also, the available valves have operating mechanism in the path of flow through the valve resulting in increased malfunction and flow cutting due to sand and trash.

It is a particularly important object of the invention to provide a new and improved form of safety valve.

It is another object of the invention to provide a well safety valve which is responsive to a predetermined flow rate in a well.

It is another object of the invention to provide a well safety valve which has an increased area over presently available valves exposed to a pressure drop caused by the rate of flow through the valve.

It is another object of the invention to provide a well safety valve which provides maximum cross-sectional area for flow into the valve.

It is another object of the invention to provide a well safety valve wherein the major operating parts of the valve are located below the inlet ports of the valve away from sand and trash in the well fluid.

It is another object of the invention to provide a well safety valve having a self-centering seal assembly between the valve operating piston rod and the valve housing.

In accordance with the invention there is provided a flow rate responsive well safety valve having a valve housing provided with a bore with side ports spaced substantially from an open lower end of the housing, a valve operating piston slidable in the bore, a piston rod, an annular valve member on the upper end of the piston rod, a valve seat in the housing above the side ports engageable by the valve member for shutting off flow into the valve housing bore, an enlarged lower end on the piston slidable in sealed relationship in the housing to provide a well pressure-responsive first area on the piston, an annular chamber between the piston and the valve housing, a side port in the piston rod opening into the annular chamber, a flow bean in the housing above the valve seat, a pressure sensing tube on the piston extending through the flow bean for communicating downstream pressure from above the flow bean through the side port in the piston into the annular chamber around a second area of the piston within the valve housing, a first spring in the annular space between the housing and the piston biasing the valve open, a detent system between the first spring and the piston for providing a high energy resistance to valve closure and for biasing the valve piston toward a valve open position when the detent system is activated, a

second spring for biasing the valve piston toward an open position, and means for connecting the valve housing to a locking mandrel to support the valve in a well bore.

5 The foregoing objects and advantages together with the specific details of a preferred embodiment of the invention will be better understood from the following description taken in conjunction with the drawings wherein:

10 FIG. 1 is a fragmentary longitudinal view in section and elevation illustrating a preferred form of well safety valve in accordance with the invention, showing the valve open;

15 FIG. 2 is a view in section and elevation similar to FIG. 1 showing the valve closed.

Referring to the drawings, a well safety valve 10 incorporating the features of the invention includes a valve housing 11, a valve operator piston 12, an annular valve member 13, a piston rod 12a between the 20 valve member and the piston, and a top sub and valve seat member 14 threaded into the upper end of the housing. A pressure reducing flow bean 15 is supported in the sub above the valve member. A pressure sensing tube 20 extends from the valve member through and 25 above the flow bean. The housing is provided with side ports 21 to permit flow into the housing and upwardly through the flow bean. The valve is biased open by a first detent spring 22 and a second main spring 23, and is closed responsive to a flow rate induced pressure differential across the piston 12 between the well pressure below the piston and a reduced pressure from above the flow bean sensed by the tube 20. The arrangement shown provides a large pressure-responsive area on the piston and entry of the fluids into the valve bore above the operating mechanism of the valve.

The valve housing 11 is a tubular member having an enlarged head portion 24 which is counterbored down to an internal upwardly facing shoulder 25 and is internally threaded along an upper end portion for securing 40 to the lower end of the top sub and valve seat member 14. The enlarged head portion of the valve housing has a plurality of circumferentially spaced downwardly opening milled slots 30 the upper ends of which extend 45 above the counterbore shoulder 25 defining large lateral ports 21 into the bore of the head end of the housing for the admission of well fluids into the valve. A bevelled seat surface 31 around the upper end of the valve member 13 is engageable with a valve seat member 32 in the lower end of the sub 14 for shutting off 50 flow through the valve from the side ports 21.

The valve member is biased open by the springs 22 and 23 and is closed by the differential between the flow related reduced pressure above the flow bean and the well pressure around the valve. The springs 22 and 55 23 are encased within the valve housing in an annular space 26 defined between the housing and the valve operating piston 12 and rod 12a. The piston rod 12a is formed integral with the valve member 13 and is threaded along a lower end portion into the upper end 60 of the piston 12 which slides within the bore of the housing 11. The housing 11 has an internal annular flange 35 forming a loose fit around the piston rod 33 and defining an upwardly facing stop shoulder 40 and a downwardly facing tapered stop shoulder 41. The 65 spring 23 is contained within the annular space 26 between the piston rod and housing compressed between the downwardly facing housing shoulder 41 and a ring

42 supported on the upper end edge 43 of the piston 12. The bore of the housing 11 is enlarged along a lower end portion 44 providing a downwardly facing stop shoulder 45 which limits upward movement of a spring retainer ring 50. The detent spring 22 is confined within the annular space 26 between the housing and the piston compressed between the retainer ring 50 and a tubular detent ball retainer 51. The lower end edge of the ball retainer 51 engages a plurality of detent balls 52 which latch and release the valve operating piston depending upon the longitudinal position of the piston in the housing. The piston head 12b of the piston 12 has an external upwardly tapered locking shoulder 53 which is engaged by the balls 52 at the longitudinal position of the operating piston shown in FIG. 1 coupling the detent spring 22 with the piston. The housing has an internal annular detent ball release recess 54 which permits the detent balls to be cammed outwardly out of engagement with the shoulder 53 to release the piston from the detent spring 22 during valve closure. Below the shoulder 53 the piston is further enlarged to a diameter forming a sliding fit within the bore of the lower end portion of the housing 11. The piston head 12b is provided with an external annular recess 55 in which a ring seal 60 is positioned for sealing between the bore wall surface of the housing 11 and the piston head.

Spaced above the upwardly facing stop shoulder 40 on the flange 35 the housing 11 is provided with an internal upwardly facing tapered stop shoulder 61 which is engageable by the tapered valve member surface 62 limiting the downward movement of the valve member 13 and the operating piston and rod within the housing as illustrated in FIG. 1. A self-centering seal assembly 63 is secured within the housing 11 above the internal flange 35 on the shoulder 40. The seal assembly is held in place by a spacer ring 64 locked by a snap ring 65 engaged in an internal annular recess within the upper end portion of the housing 11 below the stop shoulder 61. The self-centering seal assembly includes a ring 70 having a lower end edge provided with a downwardly opening annular recess in which an O-ring 71 is disposed for sealing between the ring 70 and the housing flange shoulder surface 40. The ring 70 has an internal annular recess in which a ring seal 72 is disposed for sealing between the ring 70 and the outer wall surface of the piston rod 33 below the valve member 13. The outside diameter of the ring 70 is substantially less than the inside diameter of the bore portion 73 of the housing permitting lateral movement of the seal assembly 63 within the housing to provide a self-centering feature as the rod 33 of the operating piston reciprocates through the seal during the opening and closing of the valve. Normal concentricity problems are eliminated by the seal assembly reducing manufacturing assembly costs.

The pressure sensing tube 20 is threaded along a lower end portion into the upper end portion of a blind bore 74 drilled through the valve member 13 into the upper end portion of the piston rod 12a. A side port 75 in the piston rod communicates the bore 74 with the annular chamber 26 within the housing around the piston rod so that pressure is communicated through the tube 20 and passage 74 from above the flow bean 15 into the annular chamber above the piston head 12b. The seals 71 and 72 seal the upper end of the chamber 26 and the seal 60 around the piston head seals the lower end of the annular space. This feature permits

the fluid pressure downstream of the flow bean to be applied to the operating piston above the seal 60 while well pressure is applied over the head of the operating piston below the seal 60 providing a flow rate related pressure differential applied to the piston over an area defined by the difference in the lines of sealing of the ring seal 60 with the housing wall and the ring seal 72 with the piston rod 12a.

The sub 14 is counterbored along a portion 80 defining an upwardly facing internal annular stop shoulder 81 which supports the flow bean 15 within the sub. An O-ring seal 82 within an internal annular recess 83 in the sub seals between the sub and the flow bean. The lower end 84 of a lock mandrel body is threaded into 15 the upper end portion of the sub 14 for supporting the safety valve from the lock mandrel. The lower end edge 85 of the lock mandrel body engages the upper end of the flow bean 15 holding the bean in position in the sub 14. The lower end 84 may be the lower externally 20 threaded end portion of the body of either an Otis Type X Locking Mandrel as shown at page 3458 or an Otis Type S Locking Mandrel as shown at page 3462 of the *Composite Catalog of Oilfield Equipment and Services*, 1972-73 Edition, published by World Oil, Houston, 25 Tex. Either of these locking mandrels can be landed and locked in an appropriate landing nipple included in a tubing string for supporting the safety valve in the string. As shown in the references, these locking mandrels include external packing which seals around the 30 lock mandrel within the tubing string above the safety valve 10 so that any fluids flowing upwardly in the tubing string are directed into the safety valve ports 21 when the valve is open.

In operation, the velocity safety valve 10 is connected with a suitable locking mandrel such as the Otis Types X or S, is lowered by wireline into a well, and is locked at the desired landing nipple in the well tubing. The safety valve is normally open as illustrated in FIG. 1 held by the combined forces of the springs 22 and 23. 35 Thus, as the safety valve and locking mandrel are lowered such as by wireline, fluids in the well may freely bypass the safety valve as it is lowered flowing inwardly into the valve housing through the side ports 21 and upwardly through the flow bean 15. With the safety valve 40 landed and locked in the well tubing, the valve remains open until well conditions produce a velocity through the valve sufficient to develop a pressure differential which applies an upward force on the operating piston 12 of a value high enough to overcome the downward 45 forces of the springs 22 and 23.

As the well fluids flow inwardly in the ports 21 and upwardly around the tube 20 through the flow bean 15 a pressure reduction is effected in the fluids as they 50 pass through the flow bean. The valve is designed to respond to a pressure reduction which represents a flow rate in excess of predetermined safe limits for the well system in which the valve is installed. The pressure of the producing well fluids in the tubing around the valve below the ports 21 is applied to the operating piston 12 over an area defined by the line of sealing engagement of the ring seal 60 with the bore wall surface of the valve housing below the recess 54. This force acts upwardly on the valve operator piston tending to raise the valve member 13 upwardly toward the closed position 55 on the seat 32 while the springs 22 and 23 bear downwardly on the valve operator piston biasing the valve toward the open position of FIG. 1. The reduced pres-

sure within the flowing well fluids caused by the passage of the fluids through the restricted bore of the flow bean 15 is communicated by the tube 20 downwardly into the piston rod counterbore 74 and laterally outwardly through the port 75. The reduced pressure communicated through the port 75 is transmitted within the annular chamber 26 around the operator piston 12 between the seal 60 at the lower end and the seals 71 and 72 at the upper end. The reduced pressure transmitted through the tube 20 acts on upwardly facing surfaces of the operator piston above the ring 60 to combine with the forces of the springs 22 and 23 biasing the valve toward the open position. The annular area on the piston and rod sealed by the ring seal 60 reduced by the area sealed by the ring seal 72 defines the effective area acted upon by the fluid pressure differential biasing the valve closed. When the flow rate of the well fluids upwardly in the well through the safety valve increases above the predetermined value for which the valve is set to close, the pressure differential acting over this defined area of the valve operator piston produces an upward force on the operator piston in excess of the downward force exerted by the springs 22 and 23 so that the valve operator piston with the valve member 13 begins moving upwardly. The springs 22 and 23 are simultaneously compressed. The piston head shoulder 53 lifts the detent balls 52 which raises the ball retainer 51 forcing the lower end of the detent spring 22 upwardly compressing the spring. Simultaneously, the upper end edge 43 of the piston 12 raises the retainer ring 42 lifting the lower end of and compressing the spring 23. When the balls 52 are aligned with the housing recess 54 the camming effect of the shoulder surface 53 forces the balls outwardly into the recess 54 at which positions the diameter of the piston 12 below the shoulder 53 may freely pass upwardly within the balls as shown in FIG. 2. At the moment that the balls 52 are disengaged from the shoulder 53 the detent spring 22 is no longer effective to apply a downward force against the valve operator piston so that the piston now moves upwardly against only the force of the spring 23. While the resistance of the spring 23 increases as it is compressed, the pressure differential across the piston sufficient to disengage the spring 22 is great enough to force the operator piston and valve member 13 upwardly in a snap action to the closed position shown in FIG. 2. Preferably, enough energy is stored in the upwardly moving valve system for the valve to fully close without throttling when the detent balls release the operating piston. The valve surface 31 on the valve member 13 engages the valve seat 32 in the lower end of the upper sub 14 shutting off all upward flow through the valve.

When the valve 10 is closed as shown in FIG. 2, the well remains shut-in with well fluid pressure in the tubing string below the valve acting upwardly to hold the valve closed while the only downward force on the valve is that exerted by the spring 23 and any hydrostatic pressure of fluids within the tubing string on the top of the valve member 13. The detent spring 22 is fully deactivated so long as the locking balls 52 are held outwardly in the recess 54. The diameter of the piston head 34 below the shoulder 53 holds the balls outwardly in the recess so that the downward force of the spring 22 on the ball retainer 51 is transmitted through the balls to the lower end surface of the annular recess 54 in the valve housing rather than applying the force to the valve operator piston.

The velocity safety valve 10 remains closed until the pressure differential across the valve operating piston is reduced to a value which permits the spring 23 to re-open the valve. The valve is opened by raising the tubing pressure above the valve. When the pressure is raised in the tubing above the valve, the downward force resulting from such pressure increase is applied to the top of the valve member 13 at the seat 32. This pressure increase must be sufficient to reduce the pressure differential across the operating piston 12 to a sufficient level that the downward force of the spring 23 will initiate the opening of the safety valve. It will be recognized that the valve is in the condition illustrated in FIG. 2 and the lower detent spring 22 is at this stage in the valve operation disengaged from the operator piston. Depending upon the characteristics of the springs and the extent to which they are compressed by selective use of the particular spacer rings employed, it may be necessary to raise the pressure within the tubing above the valve to a value at which the pressures are equalized across the operator piston. At any rate, when the pressure is increased above the valve in the tubing to a value sufficient to permit the spring 23 to start downward movement of the valve, the integral valve member and piston rod are forced downwardly by the spring 23 with the valve member surface 31 moving downwardly away from the seat 32 to again permit upward flow through the safety valve through the side ports 21. As the operator piston moves downwardly and the shoulder surface 53 is realigned with the release recess 54 of the valve housing and with the locking balls 52, the balls may move inwardly out of the recess 54 around the piston head side wall surface above the shoulder 53. The downward force of the spring 22 on the ball retainer 51 as applied through the balls to the bottom surface of the recess 54 causes the balls to be cammed inwardly around the piston head above the shoulder 53 so that the balls may now pass within the housing bore below the recess 54 releasing the engagement of the spring and balls with the housing and re-engaging the spring with the operator piston. The additional force exerted by the compressed spring 22 is coupled with the operator piston and in combination with the force of the spring 23 snaps the operator piston and valve member 13 downwardly to the fully open position of FIG. 1 at which the tapered surface 62 on the valve member is seated on the housing shoulder surface 61.

With the flow restored through the valve, the springs 22 and 23 hold the valve open until once again the flow rate is increased to a sufficiently high level that the pressure drop through the flow bean 15 as communicated downwardly through the tube 20 into the annular chamber around the operator piston within the valve housing reaches a value relative to the well pressure below the valve that the valve is again moved upwardly to the closed position as previously discussed.

During the upward and downward movement of the valve operator piston, the self-centering seal assembly 63 remains in sealing engagement with the housing shoulder surface 40 and the outer wall surface of the piston rod 12a maintaining an effective seal between the housing and the operator piston. This particular feature provides an effective seal with the lower manufacturing costs of a seal assembly which may be fabricated with greater tolerances since a perfect fit is not

necessary between the housing and the operator piston rod.

It will be recognized that the opening and closing characteristics of the valve may be varied by changes in the springs 22 and 23, the spacer rings 42 and 50 associated with the springs determining the initial compression on the springs, and the size of flow bean 15 used. If it is desired that the valve close at a higher rate, a larger diameter flow bean may be employed along with or alternatively thicker spacer rings and/or stronger springs. Similarly, if it is desired that the valve close at a lower flow rate weaker springs, thinner spacer rings, or a smaller diameter flow bean be installed in the valve.

The flow of the well fluids into the valve above the operating mechanism of the valve protects the valve from trash and flow cutting sand reducing malfunction and damage. The larger pressure responsive area permits operation at lower pressure differentials. The location of the inlet ports and the flow bean allows higher volumes to be handled by the valve.

What is claimed is:

1. A well safety valve comprising: a valve housing having a bore and adapted for connection with means for supporting said safety valve in a tubing string; said housing having ports for admission of well fluids to said bore; means defining a valve seat around said bore on a first side of said ports in said housing; flow rate responsive pressure reducing means in said housing on the opposite side of said valve seat from said ports; a valve member movable in said housing and engageable with said valve seat for shutting off flow through said bore from said ports; a valve operator piston connected with said valve member and movable in sealed relationship in said housing; said operator piston having a first portion thereof exposed to well fluid pressure; passage means extending to the low pressure side of said flow rate pressure reducing means for communicating a flow rate related reduced fluid pressure to an opposite second side of said operator piston for applying a flow rate related pressure differential across said piston for closing said piston when the well fluid flow rate through said valve exceeds a predetermined value; and means for biasing said operator piston in a direction to open said valve.

2. A well valve in accordance with claim 1 wherein said means for communicating said reduced pressure comprises a tube communicating at one end with said second side of said operating piston and extending through said means for reducing the pressure in fluids flowing through said valve.

3. A well valve in accordance with claim 2 wherein said tube connects into said valve member and extends in said housing bore through said valve seat and said pressure reducing means.

4. A well valve in accordance with claim 3 wherein said means for biasing said operator piston in a valve open direction comprises a spring engaged between said operator piston and said housing.

5. A well valve in accordance with claim 4 wherein an annular chamber is defined within said housing around said operator piston, said chamber communicating with said tube extending through said pressure reducing means applying said reduced pressure to said second side of said operator piston.

6. A well valve in accordance with claim 5 wherein said sealed portion of said operator piston closes one end of said annular chamber and including a self-centering annular seal assembly positioned within said housing around a reduced portion of said operator piston closing an opposite end of said annular chamber.

7. A velocity type well safety valve comprising: a housing having a bore therethrough, said housing having ports for admitting well fluids to said bore; means defining an annular valve seat within said housing toward a first end of said housing from said side ports; a pressure reducing flow bean within said housing on the opposite side of said valve seat from said side ports; an internal annular flange in said housing providing a first

15 stop shoulder facing said side ports and a second stop shoulder facing a second open end of said housing; a valve member movably disposed in said bore of said housing between said valve seat and said flange for controlling flow of well fluids from said side ports into said housing bore through said valve seat, said valve member being movable between a first closed position engaging said valve seat and a second open position spaced from said valve seat; a piston rod connected at a first end with said valve member in said bore of said housing extending from said valve member toward said second end of said housing; an operator piston connected with a second end of said piston rod and slidable in sealed relationship along an inner wall surface of said bore of said housing; a self-centering seal assembly

25 concentrically disposed between said housing bore wall surface and said piston rod secured against said first stop shoulder of said flange in said housing; said housing and said piston rod and piston being in a concentric spaced relationship defining an annular chamber within said housing around said piston rod and piston sealed towards second end of said housing by said piston and toward said first end of said housing by said self-centering seal assembly; said valve member and said piston rod having a flow passage communicating through the end surface of said valve member facing said first end of said housing and through a side wall of said piston rod into said annular chamber between said rod and said housing; a pressure sensing tube connected into said valve member flow passage extending from said valve member through said flow bean to the opposite side of said flow bean from said valve seat for communicating reduced pressure from downstream of said flow bean into said annular chamber whereby the portion of said piston facing said annular chamber is exposed to the reduced pressure downstream of said flow bean and the portion of said piston facing away from said annular chamber is exposed to well fluid pressure through said second open end of said housing;

said ring having an internal annular recess around the bore through said ring and an annular recess opening through the end face of said ring engageable with said first stop shoulder in said housing; a ring seal within said annular recess around said bore of said ring for sealing between the bore wall of said ring and said piston rod; a ring seal in said recess in said end face of said ring for sealing between said ring and said first stop shoulder in said housing; and lock ring means engaged in said housing around said housing bore holding said seal assembly against said first stop shoulder in said housing.

9. A valve in accordance with claim 8 wherein said detent means includes a second spring within said annular chamber between said housing and said piston; said housing having a third internal shoulder facing said second end of said housing; means engaging one end of said second spring with said third shoulder of said housing; a tubular locking ball retainer in said annular chamber engaged with the other end of said second spring; a plurality of locking balls disposed in said an-

nular chamber between said piston and said housing; said housing having an internal annular locking ball release recess having a tapered cam surface near said second end of said housing for camming said balls inwardly around said piston out of said release recess; and said piston having a locking shoulder defining a cam surface for engagement by said locking balls when said piston cam surface is moved in said housing toward said second end of said housing for applying a compressive force from said second spring to said piston, said spring urging said locking balls into locking relationship with said piston when said cam surface on said piston is located between said release recess of said housing and said second end of said housing, and said spring being disengaged from said piston when said piston is moved away from said second end of said housing to cam said balls outwardly into said release recess and said cam surface on said piston is positioned on the opposite side of said release recess from said second end of said housing.
